Primary Examiner — Elizabeth Albert(57) **CLAIM**

The ornamental design for a "reciprocating saw blade," as shown and described.

DESCRIPTION

FIG. 1 is a front perspective view of a reciprocating saw blade showing our new design;

FIG. 2 is a front view thereof;

FIG. 3 is a top view thereof;

FIG. 4 is a rear view thereof;

FIG. 5 is a bottom view thereof;

FIG. 6 is a left side view thereof; and,

FIG. 7 is a right side view thereof.

The broken lines in the figures are included for the purpose of showing portions of the reciprocating saw blade that form no part of the claimed design. The claimed design only includes the top forward edge and the bottom rearward edge of a reciprocating saw blade and none of the surface in between.
